CLAIM

The ornamental design for a magazine, as shown and described.

DESCRIPTION

FIG. 1 is a front side perspective view of a magazine showing our new design with both doors in an open position; FIG. 2 is a front side perspective view of the magazine showing the doors in a loading position; FIG. 3 is a front side perspective view of the magazine showing the doors in a closed position; FIG. 4 is a side view thereof; FIG. 5 is an opposite side view thereof; FIG. 6 is a front side thereof; FIG. 7 is a back side thereof; FIG. 8 is a top view thereof with the doors in an open position and showing a pair of followers inside the magazine; and, FIG. 9 is a bottom view thereof. The broken lines in FIGS. 1, 2, and 8 are included for the purpose of illustrating a portion of the magazine that forms no part of the claimed design.
